UNITED STATES PATENT OFFICE.

LEONARD H. DYER, OF GREENWICH, CONNECTICUT.

FLYING-MACHINE.

1,165,580.

Specification of Letters Patent.

Patented Dec. 28, 1915.

Application filed April 28, 1905, Serial No. 257,938. Renewed October 19, 1915. Serial No. 56,796.

To all whom it may concern:

Be it known that I, LEONARD H. DYER, a citizen of the United States, residing in the town of Greenwich, county of Fairfield, State of Connecticut, and formerly a resident of East Orange, county of Essex, State of New Jersey, have invented a certain new and useful Improvement in Flying-Machines, of which the following is a specification.

The object I have in view is the production of a device by means of which successful mechanical flight may be accomplished. My idea is to employ the lifting effect of aeroplanes combined in the complete machine with a suitable propeller, so that sufficient velocity may be secured to sustain the apparatus in the air. Many devices have been made to accomplish this purpose, but so far as I am aware, they have been unsuccessful except as small models, which have been unable to carry a person. In order to get a sufficient lifting effect of the aeroplanes, the apparatus must be propelled at high speed. Heretofore, so far as I am aware, all devices of this nature have been designed as complete flying machines before being tried. No one has attempted to produce a device which will be propelled through the air at a sufficient velocity to secure the desired lifting effect and still be attached to the stable supporting medium. All such prior devices therefore, in order to be successful must be entirely successful at the outset or else be utter failures.

Sufficient data has been secured by investigation respecting the construction and accomplishments of the aeroplanes and aerial propellers to make a flying machine practical if this were all that is necessary. The practical objections, however, have not yet been overcome, and on account of the manner in which the subject has heretofore been attacked can not be overcome unless a complete and practical machine should be made and succeed in flying at the first trial. In addition to this, no one, so far as I am aware, has yet had the practical experience necessary to undertake the proper guidance of a flying machine sufficiently large to support him. The practical difficulties lie not so much in the design of the machine with its supporting aeroplanes and propelling mechanism, as in the balancing of the machine. A flying machine of this type must

be accurately balanced, by means such as horizontal rudders or shifting weights, such means being provided to keep the device from diving or shooting upward or turning over sidewise. Such mechanism has not yet so far as I am aware reached a practical form, and will not ever reach such a form if the present methods of experimentation be followed without change. This is because as I have already pointed out, the complete machines heretofore made must either successfully fly at once or else not fly at all. As a flying machine owing to its inherent characteristics must be of a very fragile character, it is liable to become broken or entirely destroyed after every flight, until the balancing devices are perfected.

I propose to equip the device with propelling mechanism and aeroplanes and fit it for travel upon a stable supporting medium. The device will be modified according to the character of this supporting medium. If it is intended to float upon water, the device will be provided with one or more hulls, for supporting it while it is at rest and moving slowly and with hydro-planes for lifting it to the surface of the water when moving at a higher speed; if intended to travel upon the ice or snow, it will be provided with runners or skates and if for use upon land, such as the ocean beach, or some other hard and level surface, wheels will be provided.

The device will be run upon its supporting medium and the size, number and shape of the aeroplanes adjusted, and the balance of the device also adjusted until the front end of the device can be lifted up and be entirely supported in the air. In this position the device could be adjusted, and a great deal of important data as to the lifting effect of the aeroplanes and the propelling effect of the propeller could be secured. The device will be provided with a rudder, which would engage with the supporting medium and also will have an aero rudder for guiding the device horizontally. This latter rudder would be relied upon when the device is in its partially supported position, and much important data would be secured as to the effect and design of rudders. Having reached the point where a partial aerial support is secured, and the operator acquiring sufficient proficiency I would proceed to construct mechanism for guiding the device in a vertical plane. By this mechanism, the

elevated portion of the device could be raised or lowered. This mechanism having reached the perfected state, I propose to mount the entire device upon a supplemental carriage, having a support which would engage with and travel over the supporting medium, and be connected to the flying apparatus by a horizontal pivot. The support would be so arranged as to serve as a support for the rear of the machine, and allow the front part to rise up by the action of the aeroplanes. The balancing mechanism could then be adjusted so as to permit the device to assume approximately a horizontal position. When in this position, it would be connected to the supporting frame by mechanism which would prevent diving or rising of the front end, and would indicate the amount of pressure upward or downward of the elevated end of the device. The horizontal balancing mechanism could be then perfected until the device could travel on a substantially horizontal plane without need of any support other than the pivotal connection to the secondary frame. After this mechanism should become sufficiently perfected and the operator acquiring the necessary skill and experience, further developments could be made by adding mechanism such as horizontal rudders at the sides or shifting weights to prevent upsetting. To allow this to be demonstrated, instead of the two wheels, skates or hydroplanes, but a single center support would be used. After this mechanism has been perfected and the operator has acquired the necessary experience, then the supplemental frame could be lifted and the device would be entirely supported upon the air. The supplemental frame need not be discarded in the complete machine, as it will be useful in starting and bringing the machine to rest. Furthermore, I would regard it as great use in securing the proper balance of the perfected machine. The subject matter of the present invention, therefore, is not limited to machines for experimenting or instruction, but can be applied to the complete commercial devices.

In order to better understand my invention, attention is directed to the accompanying drawings, in which—

Figure 1 is a diagrammatic view of a device embodying my invention adapted for use upon the water. Fig. 2 is a similar view of a device for use upon ice or snow. Figs. 3 and 4 are devices for use upon land. Fig. 5 is a top view of a portion of the mechanism illustrated in Fig. 4. Fig. 6 is a diagrammatic side view of a refinement of a device for use upon land, the machine being at rest or proceeding slowly. Fig. 7 is a view of the same device but proceeding at sufficient velocity to elevate one end. Fig. 8 is a view of the same device, but with bal-

ancing mechanism applied and with the body approximately horizontal. Fig. 9 is an end view of the device showing the arrangement whereby the device may be supported upon a single wheel. Fig. 10 is a side view of the device entirely supported upon the air. Fig. 11 is a top view and Fig. 12 is a side view of the device illustrated in Fig. 1, showing the details of construction. Fig. 13 is a front view of the same. Fig. 14 is an enlarged section taken on the lines 14, 14, of Fig. 11, showing the construction of the hull.

In all the several views like parts are designated by the same reference characters.

In Fig. 1, 1 is a hull provided with a propelling engine 2, an aerial propeller 3, and aeroplanes 4 and 5. 6 is a rudder which is shown partially dipped into the water. In such a device when at rest, it would float in the water in the position shown in Fig. 12. When propelled it would be supported upon the hull 1 until by the action of the hydroplanes 7, the hull would be lifted out of the water and the device supported upon the surface thereof entirely by the lifting effect of the hydroplanes. Experiments could now be made with the aeroplanes 4 and 5 until a sufficient lifting effect be secured to elevate the front end of the device as shown in Fig. 1. Experiments would then be made with the aeroplanes 5 and by balancing the device so that a minimum amount of weight would bear upon the rear most hydroplane 7. The rudder 6 could then be changed in shape as shown in dotted lines in Fig. 1 so that it would no longer engage with the supporting water. The size and shape of the rudder and its controlling mechanism could then be determined to suit actual conditions.

In Fig. 2 instead of hulls 1 and hydroplanes 7, skates 8 and 9 are provided, preferably a single skate 8 and two rear supporting skates 9. The rudder 6 in this instance, is provided with an elastically depressed member 10, which will engage with the ice with sufficient force to serve as a rudder. This member could be omitted if the apparatus is in such a condition as to get along without it.

In Fig. 3 is shown a structure in which the motor 2 is connected to the rear wheels 11, the front supporting wheel 12 being connected to and operating the rudder 13 being operated by suitable mechanism (not shown). This device could be used for experimenting with the forward rudder, and also with the lifting effect of the aeroplanes.

In Fig. 4 the aerial propeller is in the rear and the device is steered by the rear wheels 11. These wheels are mounted upon supports 14 connected to the steering device 15.

In Figs. 6 to 10 inclusive, the device is

provided with an auxiliary or secondary frame 16. This frame is pivoted at 17 to the center of the machine and is provided with two or more supporting wheels 18. 5 As shown in Fig. 9, three supporting wheels in the rear are used, the center wheel 19 being connected to the secondary frame 16, while the outside balancing wheels 18 are connected to a tertiary frame 20. This 10 tertiary frame is pivoted at 21 to the auxiliary frame 16 and is provided with mechanism such as a rope 22 for lifting it and disengaging the wheels 18 from the ground. The auxiliary frame 16 may be elevated by 15 means of a rope, but is preferably provided with a rigid member 23 which will pass adjacent to the support or backbone 24 of the device, which will be provided at 25 with a suitable device for securing it to the upright 20 23, or for measuring the vertical stress upon it. The device shown in Figs. 6 and 7 is of service in ascertaining the lifting effect of the aeroplanes, the stress of the propeller and the controlling effect of the rudder 6. 25 To the device shown in Fig. 7 a horizontal rudder 26 could be attached, and data secured from experiments therewith. The controlling effect of this horizontal rudder or any other mechanism which may be 30 found useful for the same purpose could then be secured, while the machine is running in the position shown in Fig. 7. The controlling mechanism having been sufficiently perfected, the device could be run in 35 the position shown in Fig. 8, the upright 23 being secured to the backbone 24, and data secured as to the stress upon it, so that improvements could be made in the entire balancing mechanism. When the device in Fig. 40 8 is so perfected that it can travel, with the auxiliary frame 16 free to balance upon its pivot 17, then the side rudders 27, or weights or other means for accomplishing the same purpose can be provided. In order to make 45 practical experiments with these devices the tertiary frame 20 could be lifted up and the device run upon the single wheel 19.

After the device is sufficiently perfected to travel upon a single wheel the auxiliary 50 frame 16 can then be elevated, or the device lifted sufficiently clear of its supporting medium to permit it to be supported entirely upon the air. It is to be understood that in lieu of the wheels, skates or hydroplanes 55 may be employed. As shown in Figs. 6 to 10 inclusive, the front wheel 28 is mounted like a caster so that the machine will be controlled entirely by the rudder 6, but if necessary means can be provided for controlling 60 the device while all of the wheels are

upon the ground by means of the steering wheel 28.

In the practical embodiment of the invention shown in Figs. 11 to 14 inclusive, the hull 1 is very lightly made and is provided 65 with a king piece 29 arc shaped, secured at its end to the straight keel 30. Continuous frames 31 extend from the keel to the king piece and will be secured to the latter. The planking 32 is shown as extending only part 70 way up the sides, merely a sufficient distance to be above the water line. Above this point oiled silk or paper 33 or other light material can be provided to keep out the spray. Braces 34 at intervals serve as supports for 75 the hydro-planes 7, the latter being further secured to horizontal members 35. The aeroplanes as shown are supported upon the hull by suitable vertical and diagonal braces. 80

In certain of the following claims the expression "for substantial periods of time" appears. I intend this expression to mean a period of time long enough for the apparatus to be in actual flight after having arisen 85 from its supporting medium, and before it again comes back upon such medium. I also employ the term "stable medium," which I intend to mean any substance, such as land, water or ice, which is not the atmosphere. 90

The device for traveling on the water disclosed herein is not claimed in this application, but forms the subject-matter of a divisional application filed by me February 10, 1911, Serial No. 607,768. 95

Having now described my invention, what I claim and desire to secure by Letters Patent, is:—

1. In a flying machine, the combination with propelling means and an aeroplane, of 100 traveling means supported upon a stable medium, the said traveling means including means to prevent sidewise displacement of the machine, and means for disconnecting the said latter means. 105

2. In a flying machine, the combination with a frame, propelling means and an aeroplane thereon, a secondary frame pivoted thereto and carrying means for traveling upon a stable supporting medium, and a tertiary frame also carrying traveling means, the said tertiary frame preventing sidewise displacement of the machine. 110

This specification signed, and witnessed this 26th day of April, 1905.

LEONARD H. DYER.
